FIG. 4.

UNITED STATES PATENT OFFICE

2,006,574

SCAFFOLD

Alexander Kask, San Mateo, Calif.

Application February 7, 1934, Serial No. 710,188

2 Claims. (Cl. 304—7)

This invention relates to improvements in scaffolding and has particular reference to a scaffold for use by painters, decorators, plasterers and the like.

5 The principal object of the invention is to produce a portable scaffolding which is simple to manipulate.

A still further object is to produce a scaffolding which may be used as a single unit or in combination 10 with other units.

10 An additional object is to produce a scaffold which is portable and extensible.

In the accompanying drawing forming a part 15 of this specification and in which like numerals are employed to designate like parts throughout the same,

Fig. 1 is a side elevation of my scaffold as the same would appear in use,

Fig. 2 is an end elevation of a pair of my devices as the same would appear when joined one to the other,

Fig. 3 is a side elevation of one of the units of Fig. 1 in closed position, and

Fig. 4 is an enlarged detail cross sectional view 25 on the line 4—4 of Fig. 2.

Decorators, plasterers and the like usually employ saw-horses of various heights, upon which planks are placed, and the user then stands upon the planks to reach high elevations. These saw-horses are usually of standard height and the result is that in rooms of various heights it is often difficult to reach the highest points or the scaffold may be too close to the ceiling to work comfortably. Applicant has, therefore, devised a 35 scaffold which is adjustable.

In the accompanying drawing, the numerals 5 and 6 refer to upper sliding leg sections loosely secured together by a bolt 7. This bolt also serves to pivot a strut 8 to which is pivotally secured 40 braces 9 and 11. These braces have bayonet slots at their lower ends, which engage pins 13 and 14, respectively, carried upon the legs 5 and 6. Slidably mounted upon the legs 5 and 6 are lower leg sections 16 and 17. At 18 I have shown a pivoted 45 link which extends between the bottom of the legs 5 and 6 and at 20 I have shown clips which encircle the legs 16 and 17. The numeral 19 refers to a cord which passes over rollers 21 and 22 and has its lower ends connected as at 23 and 50 24 to the lower ends of the legs 5 and 6. Secured to the upper end of the legs 16 and 17, are sliders 26 which surround the legs 5 and 6 and have slots 27 formed therein through which pins 28 may be passed into holes 29 formed in the legs 5 and 6.

The result of this construction is that when the parts are in the position as shown in Fig. 1,

the operator first swings the strut 8 from its position parallel with the legs to a position at right angles thereto as shown in Fig. 2. This causes the braces 9 and 11 to move so that their bayonet slots will engage the pins 13 and 14 thus holding the strut in horizontal position. By now spreading the legs, the brace 18 will move from the position of Fig. 3 to that of Fig. 1 and will hold the legs in proper spread position. The end of the strut 8 may now be placed against the wall and another unit set up after which a plank may be placed upon the strut. When two or more units are used together, as illustrated in Fig. 2, the two struts of the units are bolted together as shown at 31, after which planks are laid upon these struts. When it is desired to elevate the unit, the operator grasps the rope 19 pulling downwardly in the direction of the lower arrow of Fig. 1, which elevates the legs 5 and 6, after which pins 28 are inserted, thus holding the legs 5 and 6 in elevated position.

It will thus be seen that I have produced a device which will accomplish the above set forth objects.

Having thus described my invention, I claim:—

1. In a device of the class described, a pair of 25 inner legs joined at their upper extremities and having clips arranged at their lower extremities, a strut pivoted between said legs, braces secured to said strut and engaging both said legs, slidable 30 legs mounted on the outside of said inner legs and having clips mounted at their upper ends and embracing the inner legs, links connecting the lower clips together, perforations in said inner legs and pins extendable through said upper clips and through said perforations to hold said inner 35 and outer legs in fixed relation, and means for elevating said inner legs relative to said outer legs.

2. In a device of the class described, a pair of 40 inner legs joined at their upper extremities and having clips arranged at their lower extremities, a strut pivoted between said legs, braces secured to said strut and engaging both said legs, slidable 45 legs mounted on the outside of said inner legs and having clips mounted at their upper ends and embracing the inner legs, pulleys carried by said clips, links connecting the lower clips together, perforations in the edges of said inner legs, and pins extendable through said upper clips and 50 through said perforations to hold said inner and outer legs in fixed relation, and means for elevating said inner legs relative to said outer legs, said means embodying a looped cord having its free ends attached to said lower clips and 55 its intermediate section reaved over said pulleys.

ALEXANDER KASK.
